UNITED STATES PATENT OFFICE

HARRY A. LEONARD, OF HOPEDALE, MASSACHUSETTS, ASSIGNOR TO DRAPER CORPORATION, OF HOPEDALE, MASSACHUSETTS, A CORPORATION OF MAINE

BUILDER MECHANISM FOR SPINNING OR WINDING MACHINES

Application filed April 9, 1929. Serial No. 353,750.

This invention relates to spinning or winding machines and is more particularly directed to the builder mechanism employed in such machines for winding yarn upon receivers or bobbins for subsequent use as filling or weft in the loom during weaving. 5

In "feeler" looms wherein the filling is replenished from time to time prior to complete exhaustion, it is usual to provide a 10 reserve supply of filling on the receivers or bobbins to insure that the last pick of the shuttle prior to replenishment shall extend the entire width of the shed under proper tension.

15 Many devices have been invented for winding such reserve supply or "bunch", as it is sometimes called, on the bobbins or receivers during the spinning or winding operation, instances of which are found in 20 the patents to Harry A. Leonard, No. 1,412, 808, April 11, 1922, and James V. Brown, No. 1,571,155, January 26, 1926.

In each of the patents to which reference has been made the bunch has been wound 25 upon the yarn receivers or bobbins without traverse. Such formation of the bunch is satisfactory for some kinds or characters of yarn, but in other cases it is desirable that the bunch shall be laid upon the receivers 30 or bobbins with a traverse, and one of the objects of the present invention is to provide spinning or winding machines of the general character shown and described in the two patents mentioned, with simple and 35 effective means for laying the bunch upon the filling carriers or receivers with a traverse.

In accordance with one aspect of the present invention, the bunch is wound upon the 40 bobbins or filling carriers or receivers with a relatively slow traverse in one direction and a relatively quick traverse in the opposite direction, and preferably the bunch will be laid upon the receivers or bobbins in 45 size and proportion suitable for subsequent use.

The invention and novel features thereof will best be made clear from the following 50 description and the accompanying drawings of one good form thereof.

In the drawings:

Fig. 1 is a side elevation of a spinning or winding machine containing the present invention, some of the parts being omitted for clearness of illustration; 55

Fig. 2 is an enlarged detail showing the position of parts during the bunch building operation, some of the parts being broken away and others in section; 60

Fig. 3 is a section on the line 3—3 of Fig. 2; and 65

Fig. 4 is an enlarged detail showing the ratchet and trip device involved in the present embodiment of the invention. 70

The spinning or winding machine herein shown is of the general type of that disclosed by the two patents mentioned, but certain features of the invention may be advantageously utilized in other characters of spinning or winding machines. 75

The machine frame 1 may be of usual construction, and has extending longitudinally thereof between the end frames the spindle supporting rail 2 and the tie rail 3. The spindle rail 2 is constituted to support one or more spindles for rotating yarn receivers 4 on which the yarn is to be wound. As the yarn is wound upon the receivers or bobbins 4, it is directed thereto by yarn guiding means which, in the present instance, consist of a ring rail 5 carrying rings 6 on which are the travelers 7 through which the yarn passes from the source of supply to the yarn receivers or bobbins. 80

Since the yarn receivers or bobbins are to be supplied with yarn for use as filling or weft in the loom, in accordance with the present invention, the yarn guides are given a traversing movement longitudinally of the receivers or bobbins of a predetermined amount and the path of such traversing movement is gradually changed from near the base towards the tip end of the yarn receivers or bobbins, in order that the yarn may be laid by a "filling wind" having a 85 service traverse, as usual in this class of machines. 90

Extending downwardly from the yarn guiding means or ring rail 5 is the lifter rod or rods 8, of which there may be any suit- 100

able number, and the lower ends whereof rest upon a roll or stud 9 carried by an arm 10 pivotally mounted at 11 on a bracket 12 supported by the machine frame.

5 Extending upwardly from the arm 10 is the segment arm 13 to which is secured a flexible connection 14 under control of the builder mechanism.

10 Pivottally mounted at 15 is the builder arm 16 having a portion 17 provided with a roll or stud 18 which normally rests upon the periphery of the builder cam 19 under the weight of the ring rail and associated parts.

15 Mounted upon the builder arm is a screw shaft 20 having a collar or threaded nut 21 to which the end of the flexible connection 14 is secured, and the screw 20 is actuated to let back on the flexible connection 14 through a chain or flexible connection 22, as more fully shown and described in the Leonard patent above mentioned, and since these parts may be of the same general character as the corresponding parts of the 25 Leonard patent, further detailed description thereof appears unnecessary.

20 Mounted on the machine frame for rotative movement is the cam shaft 23 to which is secured the builder cam 19 and also the worm gear 24, the construction being such that should the worm gear 24 be rotated, the builder cam 19 will likewise be rotated to impart through the builder mechanism connected with the yarn guides a service traverse to lay the yarn upon the receivers as hereinbefore described.

30 A worm shaft 25 carrying a worm 26 is mounted in a bearing 27 pivotally supported at 28 on an upwardly extending bracket or arm 29, and the worm shaft 25 receives its rotative movement from a suitable source of supply which as herein shown consists of a sprocket wheel 30 and sprocket chain 31.

35 The opposite end portion of the worm shaft 25 is mounted in the bearing 32 which is supported by the arm 33 pivotally connected to the machine frame at 34, and secured to the hub portion of the arm or arms 33, as indicated in Fig. 1, is a foot lever 35, the downwardly extending portion 36 of which is conveniently located for engagement by the foot of the machine attendant. The construction is such that should the foot lever 35 be depressed, the worm shaft 25 and 55 perforce the worm 26 will be moved upwardly.

40 Rigidly connected with the arm or arms 33 is a lever 37 having a weight 38 which normally acts to depress the worm 26 or lower it. These parts may all be of the same general character as more fully shown and described in the Leonard patent.

45 Loosely supported by the cam shaft 23 is a segment 39, the hub portion 40 of which is 60 shown as loosely mounted upon the cam

shaft 23. The upper portion of the segment 39 has a lateral toothed extension 41 which overlies the teeth of the worm gear 24, as more clearly indicated in Fig. 3, the construction being such that should the worm 70 26 be raised and the segment be moved into position beneath the worm and then the worm be lowered, it will engage the teeth of the segment and upon rotation of the worm 75 effect rotative movement of the segment relatively to the cam shaft 23. These parts may be substantially as shown and described in the Brown patent above mentioned.

80 The segment 39 is normally under the influence of means tending to move the segment into position beneath the worm 26 when the worm is moved upwardly, and as shown in the present instance of the invention, such means may be constituted as a weighted arm 42 secured to the segment 39 85 at 43. As hereinbefore stated, the toothed portion of the segment 41 overlies the worm gear 24, and to maintain the segment in inoperative position during the main service traverse, as indicated by dotted lines in Fig. 90 2, the left end portion of the segment, as shown, may rest upon a plain portion of collar 44 at the end of the worm. In these respects the construction may be substantially the same as that shown and described 95 in the Brown patent.

100 In accordance with the purpose of the present invention, the bunch is to be laid upon the filling carriers or receivers with a traverse, and since the segment 39 constitutes the bunch building element, means are provided for periodically connecting and disconnecting the segment with the bunch builder cam, with the result that when the segment 39 is operatively connected with the builder cam, the latter will act through the train of mechanism between it and the yarn guides to give a slow traverse to the bunch windings in one direction, and when disconnected from the segment 39, the builder 105 cam, being no longer connected with its actuating means, will rotate under the stress of the builder arm into its initial or starting position, as indicated in Fig. 1, thereby laying the next winding of the bunch in a reverse direction with quick traverse.

110 Mounted upon the bunch builder segment 39 is a pawl 45, the lower end portion of which at 46 is widened for a purpose that will presently appear. The pawl 45 is herein shown as of the plunger type mounted in a casing 47 secured to the bunch builder segment 39, and bearing upon the upper end of the pawl 45 is a spring 48, the tension of which may be regulated by an adjusting device or screw 49. To limit the movement of the plunger pawl, the latter is provided with a pin 50 extending into an elongated opening 51 in the casing 47, the construction being such that normally the pawl 45 will be 115 120 125 130 135

yieldingly held in its lowered position, as indicated in Fig. 3, with permissive movement upwardly against the tension of the spring 48.

5 Secured to the cam shaft 23 is the toothed wheel or ratchet 52, the hub portion 53 of which may be appropriately connected to the cam shaft 23 by a pin or bolt 54.

10 Secured at the side of the ratchet wheel 52 is a trip device for periodically disengaging the pawl 45 from the teeth of the ratchet. As herein shown, the trip device consists of the member 55 which may be appropriately secured to a fixed part or bearing 56 by pins 15 57 or other appropriate securing means.

10 The trip device 55 has a series of trip members 58 having inclined leading edges 59.

20 As hereinbefore noted, the lower end portion of the pawl 45 is widened, with the result that it engages between the teeth of the ratchet wheel and extends laterally to ride up the inclined surface 59 of the fixed tripping device as the bunch builder segment 25 is moved under the actuation of the worm 26.

20 The construction is such that when the bunch builder segment 39 has been released for movement into its bunch building position by upward movement of the worm, the pawl 45 will engage a tooth of the ratchet wheel 52, and as the bunch builder segment moves in the direction of the arrow, Fig. 2, it will carry the pawl 45 and ratchet 52 with it, thereby rotating the builder cam. When, however, the end of the pawl 45 contacts with and rides up one of the inclined surfaces 59 of the tripping device, the pawl will disengage the ratchet 52, thereby permitting the builder cam to move into its initial or starting position, as hereinbefore stated.

40 The tripping device may comprise any suitable number of tripping portions 58, each 45 of which is so constituted with reference to the teeth of the ratchet that it will serve to disconnect the pawl and ratchet periodically during the movement of the bunch builder segment 39 under the actuation of the worm 26.

50 When the bunch has been completed by slow traverse in one direction under the control of the builder cam and with a quick traverse in the opposite direction when the builder cam is released from the segment, the segment assumes a position indicated by dotted lines in Fig. 2, at which time it is desirable that all further automatic operation of the pawl shall cease in order that the 55 windings may be completed by service traverse. To this end the tripping device has an elongated lifting and suspending portion 60, Fig. 4, on which the pawl rests out of engagement with the ratchet teeth during 60 service winding.

From the construction described as a good practical form of the present invention it will be apparent that when a series of bobbins have been completed and the doffing operation takes place, the machine attendant may depress the treadle lever 35, thereby lifting the worm out of engagement with the worm gear 24 and simultaneously releasing the segment 39 for movement to its position beneath the worm, so that when the worm is lowered by the machine attendant it engages the teeth of the segment and the machine is thereupon started, with the result that on the first upward movement of the 70 yarn guides the traverse will be under the control of the builder cam, until the tripping device trips the pawl from engagement with the ratchet wheel, whereupon the yarn guides will descend with quick traverse, and such operations will be continued until the 75 bunch has been completed and the bunch builder segment moved into dotted line position, Fig. 2, whereupon the worm 26 will be automatically moved into engagement with the worm gear 24 under the stress of 80 the weighted lever 37 and service windings with service traverse will be continued.

85 It may be desirable at times to vary the size of the bunch or number of traverses constituting the bunch, and in accordance with the present invention, the bunch builder segment 39 is provided with a number of holes 61, Fig. 2, in which may be placed a stop pin 62 for engagement with a stop 63 to arrest movement of the bunch builder segment 90 as it moves to its initial bunch building position.

95 What is claimed is:

1. In a spinning or winding machine, the combination of yarn receivers, yarn guiding means for directing the yarn to the yarn receivers, traversing mechanism including a main builder cam, operating means for rotating the main builder cam to lay yarn upon the receivers with service traverse, bunch builder mechanism actuated by the operating means, and automatically acting devices for operatively connecting and disconnecting the bunch builder mechanism and main builder cam during the bunch building operation to cause the bunch to be wound with traverse under control of the main builder cam.

105 2. In a spinning or winding machine, the combination of yarn receivers, yarn guides for directing the yarn to the yarn receivers, a main builder cam, operating means for rotating the main builder cam to lay yarn upon the receivers with service traverse, a bunch builder segment adapted to be actuated by the operating means, and means for automatically connecting and disconnecting the bunch builder segment with the main builder cam at intervals during the bunch 110 building operation that the bunch may be 115 120 125 130

wound upon the receivers with a traverse in two directions under control of the main builder cam.

3. In a spinning or winding machine, the combination of yarn guides for directing yarn to yarn receivers, a main builder cam, a gear operatively connected thereto, a loosely mounted toothed segment, a worm movable into engagement with the gear for operating the main builder cam to lay yarn upon the receivers with service traverse and into engagement with the segment to build the bunch, and automatic means for periodically connecting and disconnecting the segment and main builder cam during the bunch builder operation to build the bunch with traverse under control of the main builder cam.

4. In a spinning or winding machine, the combination of yarn guides for directing yarn to yarn receivers, a main builder cam, a gear operatively connected thereto, a loosely mounted toothed segment, a worm movable into engagement with the gear for operating the main builder cam to lay yarn upon the receivers with service traverse and into engagement with the segment to build the bunch, automatic means for connecting the segment and main builder cam to form the bunch with slow traverse in one direction and for then disconnecting the segment and main builder cam to free the latter for movement to initial position to form the bunch with a quick traverse in the opposite direction.

5. In a machine of the class described, the combination of yarn guides for directing yarn to yarn receivers, a main builder cam and its shaft, a gear on said shaft, a vertically movable worm for operating the gear and cam, means loosely mounted on said shaft and movable into and out of register with the worm upon raising and subsequent lowering of the worm, and devices acting automatically to periodically connect and disconnect the main builder cam and said means when engaged with the worm to build the bunch with a slow traverse in one direction and a quick traverse in the opposite direction.

6. In a machine of the class described, the combination of yarn guides for directing yarn to yarn receivers, a main builder cam and cam shaft, a worm gear secured to the cam shaft for rotating it, a toothed segment loosely mounted on the cam shaft, a worm movable into operative relation with the worm gear to lay yarn upon the receivers with traverse and into operative engagement with the toothed segment to build the bunch, and means for operatively connecting and disconnecting the toothed segment and cam shaft during operation of the segment by the worm to build the bunch with traverse.

7. In a machine of the class described, the combination of a main builder cam shaft, a cam secured to the shaft, a bunch builder toothed segment loosely mounted on the cam shaft, a worm movable into engagement with the toothed segment for operating it, and means acting automatically during operation of the segment by the worm for periodically connecting and disconnecting the segment operatively with the builder cam to build the bunch with slow traverse in one direction and quick traverse in the opposite direction.

8. In a spinning or winding machine, the combination of a cam shaft, a main builder cam secured for rotative movement therewith, a builder arm bearing upon the builder cam and adapted to turn the builder cam to initial or starting position when free to such movement, a toothed bunch builder segment loosely mounted on the cam shaft, a worm movable into engagement with the toothed segment for building the bunch, a lock for connecting the segment and cam shaft to cause movement of the cam, and lock tripping means for tripping the lock periodically that the bunch may be laid with a slow traverse in one direction and a quick traverse in the opposite direction.

9. A machine of the class described having a builder mechanism, comprising, in combination, a cam shaft, a builder cam and worm gear secured to the shaft, a toothed segment loosely mounted on the shaft, a worm movable into engagement with the worm gear for rotating the builder cam to lay yarn upon yarn receivers with service traverse and into engagement with the toothed segment to build a bunch, a ratchet and pawl mechanism for operatively connecting the segment and builder cam to form the bunch winding with a relatively slow traverse, and tripping means for the ratchet and pawl mechanism to free the builder cam at the end of a slow traverse to lay the next winding of the bunch with a quick traverse.

10. A machine of the class described having a builder mechanism, comprising, in combination, a cam shaft, a builder cam and worm gear secured to the shaft, a toothed segment loosely mounted on the shaft, a worm movable into engagement with the worm gear for rotating the builder cam to lay yarn upon yarn receivers with service traverse and into engagement with the toothed segment to build a bunch, a ratchet and pawl mechanism for operatively connecting the segment and builder cam to form the bunch winding with a relatively slow traverse, tripping means for the ratchet and pawl mechanism to free the builder cam at the end of a slow traverse to lay the next winding of the bunch with a quick traverse, and means acting on com-

pletion of the bunch to inoperatively position the ratchet and pawl mechanism that the windings may be completed with service traverse.

5 11. A machine of the class described having a builder cam, a segment loosely mounted with respect to the builder cam, means for rotating the builder cam to lay winding with service traverse and for rotating the segment to build the bunch, and means automatically acting during rotation of the segment to operatively connect and disconnect the segment and builder cam at intervals that the bunch may be formed

10 15 with a relatively slow traverse in one direction and a quick traverse in the opposite direction.

12. A machine of the class described having a builder cam, a segment loosely mounted with respect to the builder cam, means for rotating the builder cam to lay winding with service traverse and for rotating the segment to build the bunch, a pawl carried by the segment, a ratchet connected to the builder cam for rotation therewith, and a fixed tripping device for periodically tripping the ratchet and pawl during rotation of the segment.

13. A machine of the class described having a builder cam, a segment loosely mounted with respect to the builder cam, means for rotating the builder cam to lay winding with service traverse and for rotating the segment to build the bunch, a pawl carried by the segment, a ratchet connected to the builder cam for rotation therewith, a fixed tripping device for periodically tripping the ratchet and pawl during rotation of the segment, and means acting on completion of the bunch to hold the ratchet and pawl out of engagement to complete the windings by service traverse.

In testimony whereof, I have signed my name to this specification.

HARRY A. LEONARD.
